UNITED STATES PATENT OFFICE.

MARTHA A. GERALD, OF CASHION, ARIZONA.

TATTING-SHUTTLE WINDER.

1,246,586.

Specification of Letters Patent. Patented Nov. 13, 1917.

Application filed October 24, 1916. Serial No. 127,450.

To all whom it may concern:

Be it known that I, MARTHA A. GERALD, a citizen of the United States, and a resident of Cashion, in the county of Maricopa and State of Arizona, have invented a certain new and useful Improvement in Tatting-Shuttle Winders, of which the following is a specification.

My present invention relates to mechanism whereby thread may be wound on shuttles used in the making of tatting.

The principal objects of my invention are to provide mechanism of the character described which is compact, durable, and by which the thread may be quickly and properly wound on the tatting shuttle; and, mechanism which is susceptible of adjustment to shuttles of varying sizes.

Another object of my invention is to provide a shuttle carrier which will separate the side plates of a tatting shuttle to facilitate winding of thread thereon.

Other objects of my invention will appear in the following detailed description, taken in connection with the accompanying drawing, forming a part of this specification, and in which drawing:

Figure 1 is a side elevation of a tatting shuttle winder constructed according to my invention.

Fig. 2 is a front elevation of the same, the shuttle being shown in section on the line 2-2 of Fig. 1.

Fig. 3 is a sectional view on the line 3-3 of Fig. 1, looking in the direction of the arrow.

Fig. 4 is a perspective view of a member forming a part of the shuttle carrier, a part being broken away to condense the view.

In the drawing, where similar characters refer to similar parts throughout the views, A designates a standard; B a tatting shuttle; C a shuttle carrier; D a device for revolvably supporting said carrier from said standard and facilitating the imparting of movement to said carrier; E a spool holder; F devices for retarding movement of a spool on said holder; and G a thread guide. If desired, a clamp H may be carried by the standard A, whereby it may be made rigid with a stationary object J, such as the marginal portion of a table.

In the example shown, the standard A is adapted to be secured to an object J, and to assume an upright position with respect thereto, the clamp H comprising a main

body portion 5 of U-shape; a screw 6, the shank of which is in screw-threaded engagement with one arm 7 of body 5; and, a disk 8 at one portion of the screw 6. The other arm 9 of body 5 is secured to the lower portion of standard A, webs 10 being provided to assist in retaining the standard rigid with the clamp. If desired, a pad 11 may be secured to the under side of arm 9, while the disk 8 may be provided with padding 12 on its upper face, the pads to engage the object J, to prevent marring of the finish thereof.

Tatting shuttles as now constructed embody a drum 13, which receives the thread, and side plates 14 and 15, secured to the ends of the drum, adapted to retain the thread in operative relation to said drum. The side plates 14 and 15 are each arcuate in their normal condition, and with their end portions nearest a plane passing transversely through the center of the drum.

In order that the thread may be properly wound about the drum 13, the carrier C is provided and includes an elongated disk 16, and means designated generally by character 17, for springing one of the side plates, that designated 15, in the example shown, of the tatting shuttle, against a face of the disk. The means 17 may comprise two members 18 and 19, each movable longitudinally of one face of the disk 16, and provided with extensions 20 projecting beyond the other face of the disk at the end portions thereof, said extensions adapted to embrace the end portions of the plate 15 of the tatting shuttle; and, a device 21 adapted to hold the members 18 and 19 in a rigid adjusted position. The device 21 may consist of a screw-threaded stub-spindle carried by the face of disk 15 against which the members 18 and 19 slide, said spindle extending through slots 22 and 23 in said members, respectively, and a thumb nut 24 turned upon said spindle adapted to hold the members 18 and 19 in binding engagement one to the other and with respect to the disk 16. The member 20 may be provided with an elongated slot 25 for a purpose to be subsequently set forth.

The device D comprises a shaft 26 extending transversely through the upper portion of standard A, said shaft having the carrier C secured to its one end portion as by being rigid with disk 16, and extending through the slot 25 of member 19; and, a crank 27

rigid with the other portion of shaft 26. If desired, washers 28 and 29 may be interposed between the crank 27 and standard A, and the carrier C and said standard.

- 5 The thread guide may be of any suitable type, and in the example shown is rigid with standard A, and provided with an eye 30, the axis of which is in a plane parallel and in close proximity to the face of disk 16 opposite to device 17.

As to the thread carrier E, it may consist of a spindle rigid with standard A, and extending from the same face thereof as guide G, while the devices F may comprise

- 15 two collars 31, provided with set-screws 32, said collars slideable longitudinally of the spool holder, and adapted to be moved and secured with their confronting faces in frictional engagement with the spool.

- 20 The operation of the winder is as follows:

The outermost device F is removed, and the spool is placed upon holder E. The thread is drawn from the spool through eye 30 of guide G, and made secure to drum 13

- 25 of the tatting shuttle in any suitable manner. The tatting shuttle is then disposed with its one side plate, that designated 15 in the example shown, against the disk 16, the end portions of said plate disposed in the

- 30 extensions 20 so that the latter embrace said end portions. This is followed by adjusting the members 18 and 19 over the face of disk 16, longitudinally thereof, until the drum 13 is in substantial alinement with 35 the axis of shaft 26, after which the thumb nut 24 is turned tight. The one plate of the shuttle is sprung against one face of the disk 16, and the shuttle is held rigid with carrier C. By imparting movement

- 40 to the carrier as through crank 27, the thread is wound upon the shuttle.

It is highly desirable that the extensions 20 have no sharp edges, although it is to be observed that the openings between the end portions of the plates of the tatting shuttle 45 are considerably larger when the shuttle is in operative relation to the carrier, and the thread guide is so arranged as to direct the run of thread so as to not engage the members of the carrier, or the plates of the shuttle. It is to be observed further that the carrier is susceptible of holding shuttles of varying sizes.

Changes in details may be made without departing from the spirit or scope of my 55 invention; but

I claim:

1. A carrier for tatting shuttles comprising in combination, an elongated disk, a member movable longitudinally of one face 60 of said disk and provided with an extension projecting beyond the other face of said disk, at one end portion thereof, said extension adapted to embrace one end portion of one side plate of the tatting shuttle, 65 a device for holding said movable member in an adjusted position, and a device carried by said disk at its other end portion adapted to embrace the other end portion of the said plate of said tatting shuttle. 70

2. A carrier for tatting shuttles comprising in combination, an elongated disk, two members movable longitudinally of one face of said disk, each member provided with an extension projecting beyond the 75 other face of said disk, said extensions at opposite end portions of said disk, and adapted to embrace the end portions of one side plate of the tatting shuttle, and a device for holding said members in an ad- 80 justed position.

MARTHA A. GERALD.
